UNITED STATES PATENT OFFICE.

GUSTAV A. LANDENBERGER, OF PHILADELPHIA, PENNSYLVANIA.

STOCKING.

1,111,658.

Specification of Letters Patent. Patented Sept. 22, 1914.

Application filed December 10, 1912. Serial No. 735,971.

To all whom it may concern:

Be it known that I, GUSTAV A. LANDENBERGER, a subject of the King of Austria, having declared my intentions of becoming 5 a citizen of the United States, residing in Philadelphia, Pennsylvania, have invented certain Improvements in Stockings, of which the following is a specification.

My invention relates to knitting and consists primarily of a special form of heel reinforcement for stockings, such as are made on the machine described and claimed in my application for United States Patent, Serial No. 731,830, filed Nov. 16, 1912, although my invention is applicable for the reinforcement of fabrics used for other purposes.

Heretofore, it was the general custom in the formation of heels for stockings to extend the latter quite high and up the back of the leg portion by making a reinforced portion or portions in which the intersecting wales of the regular knit portion of the fabric and the reinforced portion of the fabric ran parallel to each other and for the entire height of the heel portion. This produced a reinforced heel formation which ended abruptly at the top in a square-cut line of intersection between the reinforced heel portion and the regular knit portion which was very unsightly.

One object of my invention is to produce a stocking having a reinforced heel portion which gracefully intersects the regular knit 35 portions of the stocking.

Another object is to produce stockings having various designs formed by the variation of the lines of intersection between the reinforced heel portions and the regular knit portions.

A still further object is to produce stockings in which a reinforced heel portion as just described will merge into a reinforced selvage adjacent the rear seam.

These objects I attain in the following manner, reference being had to the accompanying drawings in which,

Figure 1, is a diagrammatic view of a full fashioned leg and heel knit fabric in a flat state and made in accordance with my invention; Fig. 2, is a stocking made from the fabric shown in Fig. 1 and having a foot portion knit thereto. Figs. 3 to 14 are fragmental views of similar nature to Figs. 1

and 2 and showing lines of intersections between the reinforced heel portions and the regular knit leg portions; and Figs. 15 and 16 are enlarged fragmentary views of other forms of my invention.

Referring to the drawings, Figs. 1 and 2, the knit leg portion 1 has the reinforced knit heel portions 2, the latter being lined with heavy lines in the direction of the courses and consequently at right angles to the wales; the wales not being indicated on the drawings. The courses of the reinforced portions are short as shown at 3 and gradually become longer until they reach the point 4. The variation in the length of successive courses is such as to produce a 70 concave-curved line of intersection as shown from 3 to 5 between the reinforced portion and the regular knit portion.

In Figs. 3 and 4, the courses of the reinforced portion at 6 are short and gradually 75 become long until they reach the part as indicated at 7. The variation in the length of the lines as shown in these figures is such that the line of intersection between the reinforced portion and the regular knit portion will form a straight inclined line as shown from 6 to 8.

In Figs. 5 and 6, the courses increase in length from the part 9 to the part 10 and the line of intersection between the reinforced knit portion and the regular knit portion forms a convex-curved line as shown from 9 to 11.

Figs. 7 and 8 show the courses increasing in length from 12 to 13 and the line of 90 intersection between the reinforced portion and the regular knit portion is in the shape of a step formation in which a line connecting the projecting corners will be at an inclined angle to the courses and wales of 95 the fabric, and the lines forming the step will run respectively parallel and at right angles to the line of the wale and the courses. In other words, the lines of intersection as shown at 15 will run parallel 100 to the wales and consequently at right angles to the courses, and the lines 16 will run parallel to the courses and consequently at right angles to the wales.

The form shown in Figs. 9 and 10, also 105 shows a step formation and is produced by increasing the length of the courses from 17 to 18, the latter being such that a line from

17 to 19 connecting the outer corners of the the steps will run at an incline to the wales as will also the lines 20 of intersection between the reinforced portion and the regular knit portion. The other lines 16^a forming the step will run parallel to the courses similar to the line 16 in Figs. 7 and 8. Also, in Figs. 11 and 12, a step formation is shown as forming the line of intersection between 10 the reinforced portion and the regular knit portion. In this case the courses increase in length from 21 to 22 and a line connecting the outer corners of the step formations from 21 to 23 will run at an inclined angle 15 to the wales. In this formation all the lines 24 and 25 extend at an inclined angle to the wales and the courses.

Figs. 13 and 14 show a heel formation similar to that shown in Figs. 1 and 2 and in 20 which the curved line of intersection between the reinforced portion and the regular knit portion merges and blends at 27 into a reinforced seaming selvage 26.

By constructing a stocking in a manner 25 as disclosed and using any of the various forms as described, pretty effects may be obtained at the lines of intersection between the heel and leg portions by using yarns of the same color or yarns of different colors 30 or shades of colors.

While, I have shown only one form of heel intersection merging into a reinforced seaming selvage it will be noted that any 35 of the heel intersections as shown may merge into a seaming selvage if desired, and any other modified form of intersection may also be made in connection with the reinforced selvage as shown. Also, instead of having the lines 15 as shown in Fig. 7 running 40 parallel with the wales, the same may be made to run at a curve to the line of wales as shown in Fig. 15, also the lines 16^a or 25, as shown respectively in Figs. 9 and 11, may be made curved (see Figs. 15 and 16 45 respectively) if so desired without departing from the spirit of my invention.

In the foregoing description and in the claims I have used the term "full fashioned" as describing a type of stocking which is 50 made from a varying width fabric having selvage edges seamed together, the difference in width of the fabric being produced by employing different numbers of needles

to knit different courses, or otherwise causing some of the courses to contain more 55 loops than others.

I claim;—

1. A full fashioned stocking made from a flat-knitted fabric and having a reinforced fashioned heel portion, the ends of 60 the courses of the heel reinforcement defining a line inclined to the wales and courses.

2. A full fashioned stocking made from a flat-knitted fabric having a fashioned heel 65 reinforcement, certain of whose courses are of varying lengths.

3. A full fashioned stocking made from a flat-knitted fabric having a fashioned heel reinforcement including successive courses 70 of varying lengths.

4. A full fashioned stocking made from a flat-knitted fabric and having a portion forming a fashioned heel reinforcement, the ends of the courses of the heel reinforcement 75 defining a curved line inclined to the wales and courses.

5. A full fashioned stocking consisting of a flat-knitted fabric having reinforced 80 selvage edges joined together, and including portions extending inwardly from said edges to form a heel reinforcement, certain of the courses of said heel reinforcement being of varying lengths with their inner 85 ends arranged to define a line inclined to the wales and courses of the fabric.

6. A full fashioned stocking consisting of a flat-knitted fabric having reinforced 90 selvage edges joined together, and including portions extending inwardly from said edges to form a heel reinforcement, certain of the courses of said heel reinforcement being of varying lengths with their inner ends arranged to define a line inclined to the 95 wales and courses of the fabric and blending with the line formed by the ends of the inner portion of the reinforced selvage edges.

In testimony whereof, I have signed my name to this specification, in the presence 100 of two subscribing witnesses.

GUSTAV A. LANDENBERGER.
